UNITED STATES PATENT OFFICE

2,674,911

JAR CAP REMOVER WITH CAP ENGAGING ROLLERS

Frederic A. Theis, Chicago, Ill., assignor to
Harry S. Bodanis, Chicago, Ill.

Application March 14, 1952, Serial No. 276,532

1 Claim. (Cl. 81—3.44)

1

My invention relates to implements designed for the removal of jar caps such as in mason or other types which are screwed on the jar, and one object is to provide a device of the above character which renders the removal operation easy.

A further object is to design an implement of the above character which employs a pair of jaws carrying rollers for engagement with the jar cap when the jaws are applied, such rollers operating to expand the metal of the jar cap and cause it to loosen from the threads of the jar, whereby to facilitate the unscrewing of the cap.

Another object is to apply the rollers to the jaws in opposed pairs, whereby to apply an even grip to the cap not only for expanding the metal thereof, but also for crushing or pulverizing such material as dried food or other substances lodged between the threads of the cap and the jar and operating to tighten the engagement thereof.

An additional object is to devise an implement of the above character which contains additional facilities for kitchen or home use.

With the above objects in view, and any others which may suggest themselves from the description to follow, a better understanding of the invention may be had by reference to the accompanying drawings, in which—

Fig. 1 is a top plan view of the novel implement;

Fig. 2 is a right-hand side view of the upper portion of Fig. 1;

Fig. 3 is a section on the line 3—3 of Fig. 1 and illustrating the application of the implement to a jar cap;

Figs. 4 and 5 are fragmental modifications of the implement jaws showing different types of rollers for the same;

Fig. 6 is a top plan view of a modification of the implement employing band-type of material;

Fig. 7 is a section on the line 7—7 of Fig. 6;

Fig. 8 is a second modification involving a screw-type of feed;

Fig. 9 is a section on the line 9—9 of Fig. 8;

Fig. 10 is a top plan view of a frame-type of modification which may be laid over the jar to engage its cap by a screw feed;

Fig. 11 is a front elevation of the showing in Fig. 10;

Fig. 12 is a further modification similar to that of Fig. 10, but having the form of a wall bracket; and

Fig. 13 is a front elevation of the showing in Fig. 12.

In accordance with the foregoing, specific ref-

2

erence to the drawings indicates the implement to be formed by a pair of flat steel members 20 which are crossed and have a free rivet 21 at their crossing point. In one direction from the crossing point the members 20 are developed as a pair of opposed arcuate jaws 23, these being pressed with a bead 24 or other suitable formation for purposes of reinforcement. The free ends of the jaws 23 close with a toothed formation 25, the teeth meeting when the jaws are closed. In addition, one of the jaws is formed with a finger 26 at the outer end, such finger being designed to snap into an indentation 27 made in a similar position in the companion jaw, whereby to keep the jaws closed.

The members 20 extend in a direction opposite from the pivot 21 to form a pair of shanks 30 which lie in closely spaced relation as shown in Fig. 1 when the jaws 23 are closed. However, 10 the rivet 21 carries a torsion spring 31 which is effective on the members 20 to open the jaws when the shanks 30 are separated. The shanks carry handle mountings 33; also, one of the handles carries a pivoted latch 35 which may be 15 swung over the companion handle as shown to insure the maintenance of the implement in the closed position as long as its use is not desired.

The jaws 23 of the implement carry studs 37 in opposed pairs, such studs projecting from both 20 sides of the jaws and receiving freely journaled circular rollers 38. Fig. 4 shows that a hexagonal modification 39 of such rollers may be employed if desired, and Fig. 5 shows an elliptical modification 40 which is also optional. Further, 25 while the rollers 38, 39 or 40 are described and shown in pairs, they may be used singly on the studs 37 if desired. Also, the rollers 38 may be hollow-rimmed like pulleys.

The conventional use of the implement involves the application of its double rollers to a 30 standard jar cap 42 as shown in Fig. 3. The pairs of rollers 38 are so spaced or free as to readily adapt themselves to fit between the threads of the jar cap, as shown; and the application of the implement after the roller-bearing jaws have engaged a cap as described is by 35 squeezing the handles 33 and rotating the implement back and forth around the cap. The pressure exerted by the rollers will impart an ironing-out or attenuating influence on the metal of the jar cap, so that such metal will expand slightly and loosen the cap from the jar. On the other hand, should a film or layer of congealed or hardened food substance form an adhering 40 medium between the cap and the jar, the pres-

55

sure of the rollers 38 will crush or pulverize the same and create the necessary looseness between the cap and the jar to enable the expeditious removal of the cap. It will be apparent that the influences just described will also operate where single rollers are employed; and the effect will be more forceful where the hexagonal or elliptical rollers are involved.

The modification of Fig. 6 shows the carrier of the rollers to be a loop of band metal 45, with the ends of the loop extending in companion relation to form handles 46. Fig. 7 shows that lugs 47 are bent in from one edge of the band 45 at spaced points to form bearings for the roller studs 37.

The modification of Figs. 8 and 9 is similar to the main portion of that of Figs. 6 and 7. However, it is seen in Fig. 8 that the end portions of the loop 49 carry receptacles 50 and 51, the latter being tapped in alinement for the passage of a screw 52 carried by the receptacle 50, the same having a handle 53. Thus, the rotation of this handle causes the loop 49 to contract or expand.

The modification of Figs. 10 and 11 involves a frame 55 which carries one set of the rollers 38, and a cross-head 56 which carries the opposite set of rollers. The cross-head is slidable along the frame; and a screw feed 57 controlled by a knob 58 is provided for the gathering or separation of the sets of rollers 38.

The modification of Figs. 12 and 13 is generally similar to that of Figs. 10 and 11, except that the frame in the later modification is made with a hinge 59 at the end opposite from the knob 58 for the extension of the device from a wall plate 60. Thus, when the device is not in use, it may be folded down to hang on the wall.

While the main form of the implement is largely devoted to the use described, it also affords the provision of several sundry facilities which are useful in the kitchen or home. Thus, the tooth formation 25 in the remote end of the device may constitute the jaws 23 as a pair of pliers to grip odd articles. The handle shanks 39 also have a pair of arcuate tooth formations 62 which may serve as jaws to grip caps of bottles or small jars or to turn bolts or nuts in the manner of a wrench. Further, one of the members 20 is made with a notch 65 which may be applied edgewise to certain caps for lifting the same off. Further along the same member 20, a hook-shaped notch 66 is made, which facilitates the use of the implement as a crown cap opener. A similar notch 67 is made further along the same member 20 to define an intermediate lug 68. This lug is suitable for prying use to remove pressed tops on jelly jars and the like. One of the jaws 23 is also equipped with a cylindrical pin 70 which is bifurcated at 71 to receive the

jaw and be secured to the same by a cross-rivet 72. Or, a bolt and nut may be employed to render the pin 70 detachable. The outer end of the pin 70 is flat, and the pin may be used as a hammer to drive tacks or nails wherever required.

In conclusion, it will be apparent that the novel implement is of a character to render the loosening and opening of a tight jar cap easy by reason of the roller-bearing jaws of the implement. Further, the latter is of flat construction, so that it may be thrown into a drawer with other utensils to occupy a small space while it is not in use. Finally, the implement is equipped with a number of additional features which render it handy for various and sundry uses in the kitchen or household.

While I have described the invention and its modifications along specific lines, various minor changes or refinements may be made therein without departing from the principle thereof, and I reserve the right to employ all such changes and refinements as may come within the scope and spirit of the appended claim.

I claim:

A jar cap remover comprising a pair of members of flat strip material freely pivoted to each other, a pair of handles extended from the members in one direction from the pivot, a pair of opposed arcuate jaws extended from the members in the opposite direction from the pivot, said jaws adapted to receive a threaded jar cap between them when the handles are opened out, and means carried by the jaws and applicable to the rim threads of the jar cap when the handles are gathered to impose an ironing-out influence on the material of said threads as the implement is swung around the jar cap, whereby to create a tendency in the rim to loosen from a jar on which the cap is secured, said means comprising rollers carried by said jaws in positions to engage said threads.
